UNITED STATES PATENT OFFICE.

LLOYD T. MURPHY, OF FRANKLIN, OHIO.

PROCESS AND APPARATUS FOR REDUCING PULP.

Application filed March 18, 1925. Serial No. 16,268.

This invention relates to improvements in process and apparatus for reducing pulp, in which the processes of reduction are continuous, without interruption for charging, dumping and cleaning portions of the apparatus, as the stock breaker or beater which in the common type of apparatus become clogged with foreign materials contained in the raw stock.

The main object attained in the invention consists in means associated with a stock beater or breaker for effecting separation from the mass of stock, in process of reduction in the apparatus, of heavy foreign substances, as fragments of metal, rock, glass, etc., which are found in various degrees in old paper and rag stocks, and which separate from the pulp mass and settle in the beater tub unless otherwise removed.

The common practice is to interrupt production at frequent intervals and remove the accumulation of such foreign substances by shoveling the same manually from the beater tub, then recharging the beater and continuing reduction until the apparatus again becomes clogged and reduction of the pulp stock is interfered with by the irreducible foreign matter accumulated in the bottom of the tub, when production is again interrupted while the beater tub is emptied and cleaned, production and interruption for removing the junk, thus following one another with greatly retarded output.

A further important advantage attained by the improvements of my invention consist in uniformity of grade of production, both over reduction and under reduction of the pulp stock being avoided by the means provided for separating the finished stock, i. e., the part that has been reduced to the required state of fineness, continuously from the mass of stock in process of reduction, and thus preventing over disintegration of fibrous materials which make the finer grades of pulp. Under-reduction of the coarser materials cannot result because all the stock is continuously in process of reduction by hydration and the action of the beater thereon until the required state of fineness is arrived at.

A further object attained in my invention consists in the elimination of certain units of apparatus required in ordinary reduction systems, as the settling trough and wet machine or stock thickener, and the intermediate pumps and connections for moving the stock

from one unit to another. The economies effected in the first cost of the improved apparatus, in maintenance, space saving and operating power amount to a very material item in reduced cost of production.

While the preferred use of my invention is with a continuous reduction apparatus, it will be obvious from the illustrations of the accompanying drawings and the detailed specification that the invention is also applicable to ordinary, or non-continuous stock beaters. As applied to this latter type of apparatus, the time and labor-saving features consisting in the means for removing the foreign substances from the apparatus without interrupting production are highly important.

In the drawings, which are here furnished to illustrate an application of my invention in one form:

Fig. 1 is a plane view in section on line 1—1 of Fig. 3 of a reduction apparatus having my invention applied thereto;

Fig. 2 is a cross sectional view and a detail in elevation taken on line 2—2 of Fig. 1;

Fig. 3 is a longitudinal sectional view taken on line 3—3 of Fig. 1;

Fig. 4 is a detail of the perforated backfall.

As here shown, the reduction apparatus consists of the beater tub 1 which is of the conventional type except that the tub is shown as built in concrete under the floor line 2, thus to dispose of the main bulk of the apparatus from floor space; the conventional type of midfeather 3 and beater roll 4; the perforated backfall 5, and chest 6 for separating and discharging finished pulp, being of well known special construction.

The means for separating and removing heavy foreign substances from the beater tub consist in a pit 7 sunk below the beater tub, ports 8, 9 and 10 in the bottom of the tub being provided to permit the heavy foreign substances to pass from the tub into the pit, the bottom wall 11 of the pit within the plane of the tub, as best shown in Fig. 2, being inclined to cause the foreign material to move by gravity toward the lowest point 12 of the pit within range of a bucket conveyor 13 which acts to scoop it up and deliver the same into a dump box 14 which, as here shown, is supported at a higher elevation than the stock beater.

In the dump box the heavy substances, as fragments of iron, glass, stone, etc., sink to

the bottom; lighter materials that float in water overflow the box into a trough 15—16, arranged at right angles one to the other, and leading to a save-all 17 supported in a chest 18, which may be of any suitable construction, to salvage any pulp stock remaining in the water returned from dump box 14, such material being returned to the stock beater through a conduit 19. To minimize waste by salvaging all usable pulp material from the dump box, a pipe line 25 is connected to the bottom of dump box 14 for flushing the box upward with fresh water, thus causing any pulp stock in the box to overflow the box into trough 15—16.

A pipe 20 connects the screen chest 18 with pit 7 and acts to return the excess of water to the pit. A spillway 21 is provided in pipe 20 to cause a portion of the water to be discharged from the pipe over buckets 22 of the chain conveyor 13, as the same are moved upward, thus to wash off any portions of pulp stock carried up with the foreign materials or adhering to the buckets.

It will be obvious, of course, that detail features, as save-all 17 and spillway 21, are not essential to effective operation of my improved apparatus, these features being here shown to illustrate suitable modifications in the detail arrangements of the apparatus to suit variable conditions of pulp reduction.

Another such modification consists in a gate valve 23 disposed as illustrated in Fig. 2 in the channel leading from the beater tub 35 to pit 7, the valve being adapted to regulate the opening of the channel to any desired extent to prevent too free movement of water from the beater tub to the pit.

The backfall 5 is of the perforated type, illustrated in detail Fig. 4 now well known in this art, which acts to separate finished pulp under the force of action on the mass of stock of the beater roll 4, and causes the same to be delivered into chest 6 from which the stock 45 is delivered to a chest for finished pulp by a pipe 24.

Operating connection between the beater power mechanism and the chain conveyor may be arranged in any suitable manner, the 50 arrangement here shown consisting of a pulley 26 on the beater roll shaft and a counter-shaft pulley 27 connected by a belt 28, the counter-shaft 29 being connected to the conveyor by means of chain sprockets 30—30, 55 idler sprockets 31 being employed to spread the upper course of the conveyor sufficiently to clear the dump box 14. In its lower course, the conveyor drags over a guard or "doctor" 32 which acts yieldingly to adapt the movement of the conveyor buckets to the accumulated foreign substances in the bottom of the pit.

From the foregoing detailed description and the accompanying illustrations, it will be seen that the reduction processes can be

carried on indefinitely without interruption, that delivery of finished pulp will be continuous, that both over and under reduction will be avoided, that there will be a minimum of waste and increased output.

70

Having described my invention, I claim:

1. An apparatus for reducing pulp including in combination with a stock beater, means for removing fine pulp from said beater, a space communicating with the beater tub adapted to contain stock in process of reduction and for collecting foreign materials separated from the stock, means operable coincident with the operation of the beater for removing the foreign materials together with pulp adhering thereto from said space, and means for directing a stream of water on the foreign materials so removed whereby to return the pulp adhering thereto to the beater.

85

2. An apparatus for reducing pulp including in combination with a stock beater, means for removing fine pulp from said beater, a pit opening from the bottom of the beater tub for receiving foreign materials separated by gravity from stock in process of reduction, a conveyor operable in the pit for removing said foreign materials, and means for directing a stream of water on said materials removed by the conveyor for removing adhering pulp therefrom.

90

3. In a reduction apparatus including in combination with a stock beater, a pit at a lower level than the beater tub, an opening in the bottom of the tub and a passage leading from said opening to the pit whereby heavy foreign substances will gravitate from the tub into the pit, means, as an endless conveyor, for removing the foreign substance from the pit, a receptacle adapted to receive the foreign substance, means to cause salvagable pulp stock to overflow said receptacle and to be returned to the stock beater, a pipe for returning water from said receptacle to said pit, and means to discharge water from said pipe over the foreign substances carried upwardly by said conveyor.

100

4. Apparatus for reducing old paper stock, and the like, and for removing therefrom the heterogeneous and conglomerate assortment of miscellaneous junk, such as cans, metal parts, wire, rocks, glass parts, etc., which is found therein, which comprises, in combination, a stock beater, having means for reducing the paper stock and an unobstructed opening through which the said junk may pass by gravity into a collecting pit, and a conveyor operable upon the junk passing into said collecting pit for removing the said junk from said pit.

115

5. Apparatus for reducing old paper stock, and the like, and for removing the heterogeneous and conglomerate assortment of miscellaneous junk, such as cans, metal parts,

130

- wire, rocks, glass parts, etc., which is found therein, which comprises in combination, a stock beater comprising a stock-circulating vessel, a beater roll and cooperating back-fall 5 therein for reducing the said paper stock, said vessel having an unobstructed opening in the bottom thereof in communication with an inclined passage, both said opening and passage being of generous proportions, to permit free 10 passage therethrough of junk liberated from the paper stock within the circulating vessel, a pit into which said passage discharges the said junk, and a conveyor operable within the said pit for removing therefrom the junk 15 passing into said pit.
6. Apparatus for reducing old paper stock, and the like, and for removing the heterogeneous and conglomerate assortment of miscellaneous junk, such as cans, metal parts, 20 wire, rocks, glass parts, etc., which is found therein, which comprises in combination a stock beater having means for reducing the paper stock and an unobstructed opening through which the said junk may pass by 25 gravity into a collecting pit, a conveyor for removing the collected junk from said pit without interrupting the operation of the stock beater, a receptacle into which said conveyor discharges, and means within said receptacle for recovering fibrous material carried thereinto along with the junk. 30
7. Apparatus for reducing old paper stock, and the like and for removing the heterogeneous and conglomerate assortment of 35 miscellaneous junk, such as cans, metal parts,
- wire, rocks, glass parts, etc., which is found therein, which comprises in combination a stock beater having means for reducing the paper stock, said vessel having an opening in the bottom thereof through which the said junk may pass by gravity into a collecting pit, a conveyor for removing the collected junk from said pit without interrupting the operation of the stock beater, a receptacle into which said conveyor discharges, and means for flushing the junk within the said receptacle for recovering fibrous material carried thereinto along with the junk. 40
8. Apparatus for reducing old paper stock, and the like, and for removing the heterogeneous and conglomerate assortment of miscellaneous junk, such as cans, metal parts, wire, rocks, glass parts, etc., which is found therein, which comprises in combination, a stock beater having a stock-circulating vessel, 45 means therein for reducing the paper stock, said vessel having an opening in the bottom thereof through which the said junk may pass by gravity, an inclined passage connected to said opening, a collecting pit located to one 50 side of the stock-circulating vessel into which said passage discharges, the construction being such that junk separated from the paper stock within the beater will freely pass by gravity through the said opening and passage 55 into the said pit, and a conveyor operable within the said pit for removing therefrom the junk passing thereinto. 60
